AILERON CONTROL SYSTEM FOR
AEROPLANES

Wesley Blake Henderson, Cuba, Ill.

Application February 23, 1935, Serial No. 7,893

8 Claims. (Cl. 244—29)

This invention relates to aileron control systems for aeroplanes.

As is well known, in the present or ordinary aileron control system one aileron is raised while the opposite aileron is lowered. It is recognized that a raised aileron is more efficient than one which is lowered. Not only is the lowered aileron less efficient, but it also produces a yawing tendency, which promotes a skid to the "outside" of the turn, absorbs an amount of power which otherwise would be utilized in making a faster and more easily controlled turn.

An object of the present invention is to provide means which may be readily incorporated in the ordinary aileron control system of an aeroplane whereby, when desired, the ailerons may be operated independently of one another thus overcoming the above suggested and known objection to the present type of ordinary aileron control systems.

In accordance with the present invention either aileron may be raised or lowered without affecting the position of the other aileron.

An object of the invention is therefore to provide means of the character above mentioned characterized by extreme simplicity of construction and application, and the invention together with its objects and advantages will be best understood from a study of the following description taken in connection with the accompanying drawings wherein is illustrated an application of the invention in the well known, so-called Nieuport system in which the operator turns a torque-tube by means of a stick thereby transmitting force to the "horn" which in turn transmits the force to the ailerons by means of push-pull tubes or cables.

In the drawings:

Figure 1 is a diagrammatic view illustrating the application of the invention.

Figure 2 is a side elevational view showing the application of the invention.

Figure 3 is a detail view showing the location of the parts when the system is to be operated in the ordinary manner.

Figure 4 is a view similar to Figure 3 showing the location of the parts when one of the ailerons is operated independently of the other.

Figure 5 is a view similar to Figure 4 showing the position of the parts when the other of the ailerons is independently operated.

Figure 6 is a perspective view of the actuator arm.

Figure 7 is a fragmentary side elevational view

of the actuating arm showing the latch means associated therewith.

Figure 8 is a top plan view of the actuator arm with the latch means associated therewith.

Figure 9 is an elevational view of one of the aileron control arms.

Figure 10 is a transverse sectional view through a lug equipped slide and guide rail therefor.

Figure 11 is a perspective view of the lug equipped slide.

As is thought to be well known, and as illustrated in the drawings, in the ordinary aileron control systems of an aeroplane the operator turns a torque-tube 1 through the medium of a control stick 2 to transmit movement to the ailerons 3 and 4 through the medium of control wires 5 that connect the ailerons at the top and bottom thereof to an actuator arm 6 fixed in any suitable manner to the torque-tube 1 to rotate with this tube. These cables or control lines 5 are journaled over suitably arranged pulleys as suggested in Figure 1.

In the ordinary system the wires 5 are connected directly to the actuating arm 6. However, in accordance with the present invention, instead of connecting the wires 5 directly to the arm 6 there is provided for each of the wires a control arm, and these control arms are indicated by the reference numerals 7 and 8 respectively. The control arms 7 and 8 are mounted on the tube 1 to rotate relative to the tube and are provided with apertured lugs 9 to which the control wires 5 are secured as shown.

For releasably locking the arms 7 and 8 to the arm 6 so that these arms will move as a unit, latch members 10 are pivotally mounted on the upper end of the arm 6. The latches 10 are engageable with the upper ends of the arms 7 and 8 to releasably secure the arms 7 and 8 to the arm 6. Springs 11 act on the latches 10 to normally urge the same into engagement with the arms 7 and 8.

For manipulating the latches 10 there is provided a bell crank 12 pivoted to a bracket arm 13 on the upper end of the actuating arm 6 and connected by wires or suitably flexible elements 14 to the latch members. (See Figures 7 and 8.)

When the latch members 10 are out of engagement with the arms 7 and 8 these arms may be selectively moved with the arm 6 through the medium of a pin 15 that projects from the arm 6 and is engageable with notches 16 provided in the arms 7 and 8.

Also, the arms 7 and 8 are normally urged to

rotate toward one another through the medium of a suitable spring 17 associated therewith.

For limiting rotative movement of the arms 7 and 8 under influence of the spring 17 there is provided a slide 18 having thereon relatively spaced stop blocks 19 with which are engageable lugs 20 formed on the lower ends of the arms 7 and 8. The slide 18 operates in a suitable track or rail 19.

For operating the latches 10 and the slide 18 there is suitably mounted on the control stick 2 a hand lever 21 connected to a main cable 22 operating through a suitable sheathing 22a retained in place as at 25—25. This cable 22 is connected with the bell crank 12 through the medium of a cable section 23 and with one end of the slide 18 through the medium of a cable section 24. Cables 23 and 24 are trained over suitable pulleys arranged in the ends of a bracket 26 suitably mounted on the torque tube 1, which latter is journaled in suitable bearing standards 27. The slide 18 is normally urged in one direction through the medium of a coil spring 28 secured to one of the lugs 19 and anchored at one end to one of the bearing standards 27 (see Figure 2).

From the above it will be apparent that when the arms 7 and 8 are latched to the actuating arm 6 as shown in Figure 3 a manipulation of the rod 22 will cause an operation of the ailerons 3 and 4 in the usual manner, that is to say, one of the ailerons will move upwardly and the other downwardly depending upon the direction in which the stick 2 is moved.

However, and in accordance with the present invention, when it is desired, for example, to move the aileron 3 without affecting the other aileron, for example, the aileron 4 the operator presses the hand lever 21 toward the stick 2 which releases the latches 12 and draws the slide 18 into position so that for example, one of the lugs 19 will be in the path of the lug of the proper control arm 8. The operator then moves the stick 2 in the proper direction, and the pin 15 on the arm 6 engages the notch 17 in the proper arm 7 or 8, for example, the arm 8, said arm together with the arm 6 will swing in the same direction to assume, for example the position shown in Figure 4 thus operating the aileron 3. Movement of the other arm, for example, the arm 7 will be prevented by reason of the engagement of its lug 20 with one of the lugs 19. Thus, it will be seen that the aileron 3 may be operated independently of the aileron 4.

To operate the aileron 4 independently of the aileron 3 the operation is substantially the same, the arm 7 being resorted to obtain this operation as will be clear from a study of Figure 5.

It will be understood that my improved control system is not confined solely to aircraft; and that the system may be used equally as well with "wheel" type control, or any other type of control which will impart force to the actuating arm of the control system; and that the invention comprehends the use of either cables, as shown, or tubes if the latter be found desirable.

Having thus described the invention what is claimed as new is:

1. In an aileron control system for aeroplanes, the combination with a torque tube, a control stick connected therewith for rotating the tube, of means connecting the ailerons with the torque tube for operating the latter, to effect either a conventional simultaneous operation of the ailerons or a selective operation of the ailerons independently of one another, optionally, said means

including an actuating arm mounted on the torque tube to rotate therewith, a pair of aileron control arms mounted on the torque tube and relative to which the tube is rotatable, latch means mounted on the actuator arm and engageable with the control arms for locking said arms together to rotate as a unit whereby to cause a raising of one of the ailerons and a lowering of the other upon a rocking movement of the torque tube, means for releasing said latch means, and interengaging means on the actuator arm and the aileron control arms operable, upon release of said latch means for transmitting movement from the actuator arm to the selected control arm to thereby effect an operation of a selected aileron relative to and independently of the other aileron upon rotation of the torque tube.

2. In an aileron control system for aeroplanes, the combination with a torque tube, a control stick connected therewith for rotating the tube, of means connecting the ailerons with the torque tube for operating the latter, to effect either a conventional simultaneous operation of the ailerons or a selective operation of the ailerons independently of one another, optionally, said means including an actuating arm mounted on the torque tube to rotate therewith, a pair of aileron control arms mounted on the torque tube and relative to which the tube is rotatable, latch means mounted on the actuator arm and engageable with the control arms for locking said arms together to rotate as a unit whereby to cause a raising of one of the ailerons and a lowering of the other upon a rocking movement of the torque tube, means for releasing said latch means, and interengaging means on the actuator arm and the aileron control arms operable, upon release of said latch means for transmitting movement from the actuator arm to the selected control arm to thereby effect an operation of a selected aileron relative to and independently of the other aileron upon rotation of the torque tube.

3. In an aileron control system for aeroplanes, the combination with a torque tube, a control stick connected therewith for rotating the tube, of means connecting the ailerons with the torque tube for operating the latter, to effect either a conventional simultaneous operation of the ailerons or a selective operation of the ailerons independently of one another, optionally, said means including an actuating arm mounted on the torque tube to rotate therewith, a pair of aileron control arms mounted on the torque tube and relative to which the tube is rotatable, latch means mounted on the actuator arm and engageable with the control arms for locking said arms together to rotate as a unit whereby to cause a raising of one of the ailerons and a lowering of the other upon a rocking movement of the torque tube, means for releasing said latch means, and interengaging means on the actuator arm and the aileron control arms operable, upon release of said latch means for transmitting movement from the actuator arm to the selected control arm to thereby effect an operation of a selected aileron relative to and independently of the other aileron upon rotation of the torque tube, said aileron control arms being provided with stop lugs, a slide mounted to move in a plane parallel with the torque tube and provided with stop lugs with which the lugs of the aileron control arms are engageable selectively to retain a selected aileron control arm against rotation incidental to a rotation of one of the aileron control arms.

- with stop lugs, a slide mounted to move in a plane parallel with the torque tube and provided with stop lugs with which the lugs of the aileron control arms are engageable selectively to retain a selected aileron control arm against rotation incidental to a rotation of one of the aileron control arms, and means for shifting said slide member incidental to a manipulation of said latch means.
4. In an aileron control for aeroplanes of the type including a torque tube, a control stick connected with the tube for manipulating it, and cables connected with the ailerons for transmitting movement of the torque tube for controlling the ailerons; means operatively connecting said cables with the torque tube for transmitting movement of the torque tube to the ailerons either simultaneously or selectively, optionally, said means including arms mounted on the torque tube, one for each aileron cable, and relative to which the torque tube is rotatable, remote control means for securing said arms to the torque tube for rotation therewith as a unit to simultaneously operate the ailerons, said means also including means for securing a selected one of said arms to the torque tube for rotation therewith independently of the other of the arms to thereby effect an operation of a selected aileron independently of the other aileron.
5. In an aileron control for aeroplanes and in combination with a torque tube, ailerons, and cables for transmitting movement of the torque tube to the ailerons; control arms loosely mounted on the torque tube and connected with said cables, means for placing said control arms into and out of fixed relation relative to the torque tube for transmitting movement of the torque tube to the ailerons for actuating the aileron either simultaneously or selectively independently of one another, optionally.
6. In an aileron control system for aeroplanes, the combination with a torque tube, a control stick connected therewith for rotating the tube, and cable means for transmitting movement of the torque tube to the aileron; of means normally loose on the torque tube and connecting

the cables with the torque tube, remote control means for placing said first named means into and out of fixed relation to the torque tube for movement therewith to transmit movement to the ailerons either simultaneously or selectively and independently of one another, optionally, and additional means cooperable with the first named means to insure against casual manipulation of one aileron during the operation of the selected aileron.

7. In an aileron control for aeroplanes wherein is included a torque tube and cables for transmitting movement of the torque tube to the ailerons for manipulating the latter, of means connecting the cables with the torque tube for transmitting movement of the torque tube for operating the ailerons together simultaneously or selectively independently of one another optionally, said means including control arms mounted on the torque tube, means for placing said arms into and out of fixed relation relative to the torque tube, and remote control means cooperable with said arms for retaining a selected one of said arms against casual rotation incidental to a positive movement of the other of said arms for operating a selected aileron.

8. In an aileron control for aeroplanes wherein is included a torque tube and cables for transmitting movement of the torque tube to the ailerons for manipulating the latter, of means connecting the cables with the torque tube for transmitting movement of the torque tubes for operating the ailerons together simultaneously or selectively independently of one another optionally, said means for placing said arms into and out of fixed relation relative to the torque tube, and remote control means cooperable with said arms for retaining a selected one of said arms against casual rotation incidental to a positive movement of the other of said arms for operating a selected aileron, said means including lugs on said arms, a slide, guide means on the slide paralleling the torque tube, and spaced lugs on the slide for cooperation with the lugs on said arms.

WESLEY BLAKE HENDERSON.
